(57) **CLAIM**

The ornamental design for a combined reversible steering wheel cover and bag, as shown and described.

DESCRIPTION

FIG. 1 is a front view of the reversible steering wheel cover and bag exposing a reflective surface.

FIG. 2 is a rear view of the wheel cover and bag of FIG. 1.

FIG. 3 is a left side view of the wheel cover and bag (the right side view being substantially identical) of FIG. 1.

FIG. 4 is a bottom view of the wheel cover and bag (the top view being substantially identical) of FIG. 1.

FIG. 5 is a front view of the reversible steering wheel cover and bag exposing a non-reflective surface.

FIG. 6 is a rear view of the wheel cover and bag of FIG. 5.

FIG. 7 is a left side view of the wheel cover and bag (the right side view being substantially identical) of FIG. 5; and, FIG. 8 is a bottom view of the wheel cover and bag of FIG. 5 (the top view being substantially identical) of FIG. 8.
